UNITED STATES PATENT OFFICE.

FREDERIC K. PLUMBLY, OF BUFFALO, NEW YORK.

BALLOT-BOX.

SPECIFICATION forming part of Letters Patent No. 478,264, dated July 5, 1892.

Application filed April 28, 1892. Serial No. 430,970. (No model.)

To all whom it may concern:

Be it known that I, FREDERIC K. PLUMBLY, a citizen of the United States, residing at Buffalo, in the county of Erie and State of New York, have invented certain new and useful Improvements in Ballot-Boxes; and I do hereby declare the following to be a full, clear, and exact description of the invention, such as will enable others skilled in the art to which it appertains to make and use the same, reference being had to the accompanying drawings, and to figures of reference marked thereon, which form a part of this specification.

The object of my invention is to provide an improved form of ballot-box, so constructed and arranged as to prevent the admission of ballots thereto not only during the interval between the closing of the polls and the time at which the ballots contained therein are removed to be counted, but before the box is placed in position for use. I accomplish this by means of a plate open or slotted at one side only and so arranged as to be turned or reversed in position, so that when the open or slotted side in the plate registers with the slot in the cover of the box, the ballots can be freely admitted; but when the position of the plate is reversed the slot in the box is securely covered. The plate in both of these positions may be independently locked at more than one point, each lock with its key being of different construction, the principal object being to place the manipulation of the independent locks in the hands of the duly-appointed officials of the different parties, thereby removing the control of the box from any one person or party. I will now proceed to describe the manner in which I have carried out my invention.

40 In the drawings, Figure 1 is an elevation of my improved ballot-box. Fig. 2 is a central vertical section. Figs. 3 and 4 are respectively top plan views of the ballot-box opened and closed. Fig. 5 is a segmental vertical section in a different plane from that of Fig. 2, and Fig. 6 is a modified form of plate 9.

Referring to the drawings, 1 is the body or side, 2 the removable top or cover, and 3 the bottom of the box, forming a receptacle preferably of cylindrical shape. The body or sides 1 may be of galvanized iron, preferably corrugated for the sake of increased rigidity.

The top or cover 2 I prefer to be of sheet metal, and the bottom 3 may be of either cast or sheet metal. Upon the top or cover 2 and 55 cast integral with it or rigidly secured thereto are the posts or uprights 4, having the slots or apertures 5. A rod 6, secured in the central base 7 of the bottom 3, passes up loosely through the central orifice 8 in the cover and 60 has its upper end screw-threaded for locking purposes, as will be hereinafter shown.

9 is a plate having a screw-threaded central orifice 10, which engages with the fastening-rod 6 to lock the cover upon the box. 65 The plate 9 is of a size and shape adapted to be easily turned between the posts 4 of the cover and upon the screw-threaded end of the rod 6, and is provided on opposite sides with the posts or uprights 11, between which 70 at their upper ends is arranged the handle 12 for both turning the plate 9 and carrying the box.

In the posts 11 are the apertures 13, which register with the apertures 5 in the post 4 when the plate 9 is in either position.

14 is the open side of the plate 9, which when the plate is in the position shown in Figs. 3 and 5 registers with the ballot-slot 15 in the cover 2.

16 16 are the padlocks, and 17 17 their keys, each set being of different construction, if desired, to independently lock the two ends of the plate 9 to the cover by being passed through the sets of apertures 5 and 13 in the posts 4 85 and 11.

The parts are put together as follows: The cover 2 is placed upon the body 1 of the box, as shown, the upper screw-threaded end of the rod 6 projecting above the top surface of 90 the cover, which rests centrally upon a shoulder of the rod 6. The screw-threaded orifice 10 of the plate 9 is next engaged with the projecting screw-threaded end of the securing-rod 6, and the plate 9 is turned down thereon until 95 at or very near the top surface of the cover 2. The plate 9 may then be secured in either position by the padlocks 16 to either open or close the ballot-slot 15 in the cover for the purposes already stated, at the same time securely locking the cover upon the box.

In Fig. 6 is shown a modification of the plate 9, in which a slot 18 in the plate takes the place of the open side 14. (Shown in Figs.

3 and 4.) Either form may be used with equal effect, or the plate might be cut away entirely across the open side.

It is to be understood that similar padlocks 5 or one padlock alone may be employed, if desired, so that one person can control the locking and unlocking of the box. The plate 9 might be locked at more than two places and reversed in position without connection with 10 the locking-rod 6, which could be independently operated or replaced by other well-known locking devices for securing the cover to the box.

It will be seen that the box is constructed 15 in what is known as "knockdown form," the parts when separated being adapted for close packing. The body 1, of sheet metal, is in a single piece, its ends being secured together along one side by the fastening-bolts 19, the 20 whole secured to the bottom 3 with similar bolts 20. In this manner the separated parts can be compactly arranged for transportation and quickly and readily put together when required for use, thereby permitting of a great saving in the carrying cost.

I claim—

1. In a ballot-box, the combination, with its top or cover provided with a ballot-slot, of a locking-plate open or slotted on one side only, 30 said plate being adapted to be turned or reversed in position to open or close the ballot-slot and to be locked in either of its positions at one or more points, as and for the purpose stated.

35 2. In a ballot-box, the combination, with its top or cover provided with a ballot-slot, of a locking-plate open or slotted on one side only, said plate being adapted to be turned or reversed in position to open or close the ballot-slot and to be secured in either of its positions 40 at more than one point by separate and independent locks, as and for the purpose stated.

3. In a ballot-box, the combination, with its top or cover provided with a ballot-slot, of a locking-plate open or slotted on one side only, 45 said plate being adapted to be turned or reversed in position to open or close the ballot-slot and to be secured in either of its positions

at more than one point by separate and independent locks of different constructions, as 50 and for the purpose stated.

4. In a ballot-box, the combination, with its top or cover provided with a ballot-slot and means for securing said cover to the box, of a locking-plate open or slotted on one side only, 55 said plate being adapted to be turned or reversed in position to open or close the ballot-slot and to be secured in either of these positions at more than one point by separate and independent locks and to simultaneously secure the cover to the box, as and for the purpose stated.

5. In a ballot-box, the combination, with the top or cover 2, provided with the ballot-slot 15 and posts 4 4, with apertures 5 5, of the plate 65 9, with open side 14 and having apertured posts 11 13 and handle 12, the whole adapted to be locked through the apertures in the posts, substantially as and for the purpose stated.

6. In a ballot-box, the combination, with the top or cover 2, provided with ballot-slot 15, central aperture 8, and posts 4 4, with apertures 5 5, and the securing-rod 6, screw-threaded at its upper end and secured to the bottom 75 3 at its lower end, of the plate 9, with open side 14 and centrally screw-threaded aperture 10 and having apertured posts 11 13 and handle 12, the box, its cover, and the plate, all adapted to be locked through the apertures 80 in the posts, substantially as and for the purpose stated.

7. A knockdown ballot-box consisting of the body 1, of one piece of sheet metal, bolted together along the side, the bottom 3, bolted 85 to the body 1, and the removable top or cover 2, secured in place by the screw-threaded rod 6 and any suitable locking mechanism.

In testimony whereof I have signed my name to this specification in the presence of 90 two subscribing witnesses.

FREDERIC K. PLUMBLY.
